TOILET TANK FLOAT BALL
Antimo M. Glorioso, 12606 Mt. Overlook Ave.,
Cleveland, Ohio 44129
Filed Sept. 1, 1964, Ser. No. 393,554
6 Claims. (Cl. 4—56)

This invention relates to toilet tank supply regulators and more particularly to an improved float ball.

It is an object of the present invention to provide a float ball which will be less bulky than that of the prior art type and will be more stable in function within toilet tanks.

Another object of the present invention is to provide a toilet tank float ball which, when installed properly, will not interfere with or touch the flush ball, thus providing complete freedom for correct functioning within the toilet tank.

A further object of the present invention is to provide a float ball which will have oppositely opposed wing members which will serve for better overall functioning of the water regulation within the tank.

Other objects of the invention are to provide a toilet tank float ball bearing the above objects in mind which is of simple construction, has a minimum number of parts, is inexpensive to manufacture and efficient in operation and use.

For other objects and for a better understanding of the invention, reference may be had to the following detailed description taken in conjunction with the accompanying drawing, in which:

FIGURE 1 is a side view of the present invention shown in elevation and partly broken away;

FIGURE 2 is an end view of FIGURE 1.

Referring now more in detail to the drawing, a toilet tank float ball 10 made in accordance with the present invention is shown to include a bulbous, hollow body 12 having a pair of outwardly extending wings 14 which are in alignment with the central plane of a cylindrical extension 16. The float rod 18 is threadingly received within end wall 20 of float ball 10 and providing a means for securing float ball 10 to the regulating mechanism (not shown) of the toilet tank.

In use, the toilet is flushed in the well known manner and the tank water and tank float ball 10 lower with the water lever, and as the flush ball rises with the trip lever handle, the two balls do not interfere or touch each other in any manner. Thus, complete freedom for proper functioning is achieved. This is particularly evident after the present invention is used in the toilet tank for the period of a year or more.

It shall be recognized that the wings 14 of float ball 10 give a restraining action to the regulating mechanism of the toilet tank by the pressure of the water upon the surfaces of wings 14.

It shall further be recognized that the present invention prevents the customary tendency for the float ball to touch the flush ball, which allows the water in the tank to run continuously.

2

It shall be noted that float ball 10 made of copper, aluminum, plastic or the like.

While various changes may be made in the detail construction, it shall be understood that such changes shall be within the spirit and scope of the present invention as defined by the appended claims.

What I claim as new and desire to protect by Letters Patent of the United States is:

1. An improved float ball for toilet tank regulating mechanisms comprising, in combination, a bulbous, hollow body serving as a float to open and close the valve mechanism of a toilet tank, a hollow, cylindrical extension carried by said hollow body of said float ball providing means for securing said float ball to the brass rod of the regulating valve mechanism of the toilet tank, a pair of wing members carried by said hollow body providing a means of preventing said float ball from touching the flush ball and providing an absolute shutoff for the toilet tank regulating mechanism when the tank is full.

2. The combination according to claim 1 wherein said hollow body of said float ball is circular in configuration in one plane and an extension of said hollow body is cylindrical and elongated in configuration, providing a means for threadingly receiving the valve mechanism control rod.

3. The combination according to claim 2 wherein said pair of wings carried by said float ball are extending and secured to the outer surface of said hollow body of said float ball and said wings provide a restraining and dampening action due to the pressure of the water within the tank.

4. The combination according to claim 3 wherein the outer edges of said wings of said hollow body of said float ball are tapered to a point, and said wings are parallel with each other and are in alignment with the central axis of said hollow body and said cylindrical extension of said float ball, and serving to stabilize said regulating mechanism of said toilet tank and preventing said float ball from touching the flush ball during the operation of said toilet tank mechanism.

5. The combination according to claim 4 wherein the end wall of said extension of said hollow body of said float ball is internally threaded thus threadingly receiving and securing said control rod which is pivotably secured to the regulating valve mechanism of said toilet tank.

6. The combination according to claim 5 wherein said wings secured to said hollow body of said float ball are of such design as to prevent water from continuously running within said tank by the pressure action of the water within said tank against the surfaces of said wings.
